PIANO ACTION

Charles F. Smith, 835 Circle Ave., Forest Park, Ill.
Filed Aug. 13, 1963, Ser. No. 301,827

4 Claims. (Cl. 84—243)

The present invention relates to an escapement action for a grand piano.

Escapement actions have followed a standardized construction for many years. In this structure, the jack contacts the hammer knuckle and lifts it to raise the hammer against the string. There has long existed a problem with respect to friction drag between the jack and the knuckle. This friction drag results in sluggish action of the keys, and obviously adds to the inertia. Considerable finger strength must be developed for playing the piano over long periods of time. Furthermore, a very soft tone cannot be struck in a reliable manner because the player cannot be completely sensitive to the extent of the friction drag.

It is an object of the present invention to provide an improved construction which will minimize the friction between the jack and the hammer knuckle.

A further object of the invention is to provide an adjustment whereby the amount of friction drag between the knuckle and jack can be readily changed and regulated. Some piano players, particularly professional artists, have become accustomed to full friction drag between the jack and knuckle and have developed such finger strength that any change in this drag would be objectionable to them. In order to meet the requirements of such persons, my invention permits the adjustment of the friction drag.

In the accompanying drawing:

FIGURE 1 is a side elevation of a grand piano escapement action;

FIGURE 2 is a side elevation of the hammer butt, knuckle and spoon for positioning the jack with respect to the knuckle;

FIGURE 3 is a front elevation, partly in cross section of the hammer butt, knuckle and spoon for positioning the jack;

FIGURES 4 and 5 are side elevations, partly in cross section, of the knuckle and jack and associated parts. FIGURE 4 shows the jack contacting the knuckle in position to lift it; FIGURE 5 shows the knuckle and jack after the escapement action, with the jack moved out from under the knuckle.

In the preferred embodiment of my invention, which is illustrated in the drawing, there is shown a key frame or base 11 which carries a plurality of front key pins 12 each of which is surrounded by a felt washer 13. The base 11 also carries a balance rail 14 which supports a plurality of balance key pins 15. The keys 16 are held in position by the felt washer 17. The back end of each of the keys 16 carries a felt pad 18 adapted to engage the damper lever which is carried by the bracket or frame 19. Each key is provided with a capstan screw 21, positioned at an intermediate point between the rear extremity of the key 16 and the balance key pin 15. The capstan screw 21 bears against a felt surface 22 carried by a dependent portion 23 of a whip or wippen 24. The wippen 24 is supported at its rear end by a whip flange 25 which is secured by a screw 26 to a whip rail 27. The whip rail 27 is secured to the bracket or frame 28.

The forward extremity of the whip 24 is pivotally connected to the jack 29, intermediate the two ends of the jack. A jack regulating screw 30 is carried by the jack. This screw 30 has a jack butt 31 which contacts the spoon or stop 32.

The bell crank extremity of the jack 29 is arranged to engage the regulating button 33 carried by the rail 34.

The whip 23 carries a repetition lever flange 35. Piv-

2

otally connected to this flange is a repetition lever 36, one end of which carries a regulating screw 37. Adjacent the forward extremity of the repetition lever 36 there is an opening through which passes the upper end of the jack 29. Both the jack 29 and the repetition lever 36 engage a knuckle 38, which is carried by the hammer butt 39. The hammer butt 39 is pivotally connected to a butt flange 40, which is mounted on the hammer rail 34. The hammer butt 39 extends rearwardly to a reduced diameter portion known as a hammer stem 41.

The hammer stem 41 carries at its outer extremity a hammer 42 which, when raised to the dotted line position shown in FIG. 1, will strike the piano string 43. When a key is struck and held down, the back check 44 carried at the rear end of the key 16 is raised to limit the downward motion of the hammer 42.

The forward or outer end of the repetition lever carries a button 45 which strikes a stop 46 positioned on the hammer flange during upward movement of the repetition lever. A spring 47 is connected to the repetition lever and the jack, as shown in FIG. 1. The tension of the spring urges the repetition lever upwardly and urges the jack under the knuckle.

The foregoing parts constitute the standard or common grand piano action. In accordance with the present invention I modify this standard action by providing a positioning member 48 extending downwardly immediately rearwardly of the knuckle 38. This positioning member or spoon serves to position the jack away from the spoon or stop 32 when the key is released. On the next stroke, therefore, the jack is not held against rearward movement by the stop 32 but is free to move rearwardly with the knuckle as the knuckle is raised. There is thus no frictional drag between the jack and the knuckle during upward movement of the knuckle and jack.

The spoon or positioning member 48, being carried by the hammer butt 39, swings rearwardly with the knuckle as the hammer butt is moved upwardly and accordingly does not block the slight rearward movement of the jack. FIGS. 4 and 5 illustrate the position of the knuckle, jack and positioning member just before and just after the escapement of the jack from under the knuckle.

The operation of the action is as follows:

When the key is depressed the jack 29 raises the knuckle and the hammer stem so that the hammer 42 hits the wire 43. The hammer rebounds and is caught by the back check 44. The jack 29, in its upward movement, has struck stop 33 causing the opposite end to move sharply out from under the knuckle to a forward position as shown in FIG. 5. The repetition lever 36 is depressed by reason of its movement against stop 46.

When the key is released, the back check 44 is lowered and no longer supports the hammer. The repetition lever 36 supports the hammer at this point so that the jack can move back under the knuckle for the next stroke. As the jack moves rearwardly under the knuckle, its movement is checked by the contact of the button 31 with the spoon 32. As the hammer stem drops into its lowest position the spoon or positioning member 48 contacts the jack and moves it forwardly so that the button 31 is clear of spoon 32. With the jack thus positioned clear of the spoon 32, the jack contacts the knuckle in only one position on upward movement, and does not slide across the surface of the knuckle.

By adjustment of the screw 30 the amount of clearance between the button 31 and the stop 32 can be regulated to control the amount of friction drag between the knuckle and the jack. If a pianist accustomed to playing with the old friction drag desires such drag, it can be provided in full or to the desired degree.

It is to be understood that the invention is not limited

to the particular embodiment which has been described and shown in the drawing, and such variation in the construction may be made as is commensurate with the scope of the invention as set forth in the following claims.

What is claimed is:

1. The combination in a grand piano action comprising a hammer butt carrying on its underside a knuckle, a repetition lever and jack arranged to actuate said hammer butt by engagement with said knuckle, and means on said hammer butt for engagement with said jack to position said jack under said knuckle.

2. The combination in a grand piano action comprising a hammer butt carrying a hammer, a knuckle mounted on the underside of said butt, a jack, a whip, a stop mounted on said whip for limiting the movement of said jack, and a member on said hammer butt for engagement with said jack whereby said jack may be moved clear of said stop.

3. In a grand piano action comprising a hammer butt having a knuckle on its underside, a repetition lever and jack arranged to actuate said hammer butt by engagement with said knuckle, the improvement which resides

in the provision of a spoon on said hammer butt for engaging said jack to position the jack under the knuckle.

4. In a grand piano action comprising a hammer butt having a knuckle thereon, a repetition lever and jack arranged to actuate said hammer butt by engagement with said knuckle, the improvement which resides in the provision of an adjustable stop member for limiting the movement of said jack, and the provision of a spoon on the hammer butt for positioning the jack with respect to the stop.
